UNITED STATES PATENT OFFICE.

JOHN LANSON ADAMS, OF NEW YORK, N. Y.

DESIGN FOR A MOLD FOR PAVING-BLOCKS.

SPECIFICATION forming part of Design No. 28,715, dated May 24, 1898.

Application filed March 28, 1898. Serial No. 676,503. Term of patent 7 years.

To all whom it may concern:

Be it known that I, JOHN LANSON ADAMS, a citizen of the United States, residing in the city of New York, (borough of Manhattan,) 5 in the county of New York and State of New York, have invented and produced a new and original Design for a Mold for Paving-Blocks, of which the following is a full, clear, and exact specification.

10 The design relates to a frame adapted to receive a plastic material, the frame, with the inclosed plastic material, being intended for paving purposes.

Figure 1 is a perspective view of a frame 15 embodying the features of my design, and Fig. 2 is a plan view of the frame.

The design consists of side walls A and end walls B, so grouped as to form a skeleton parallelogrammatic figure, in which figure partitions C are diagonally arranged, the partitions appearing integral with the surfaces that they connect. 20

I claim—

The design for a mold for paving-blocks herein shown and described.

JOHN LANSON ADAMS.
